UNITED STATES PATENT OFFICE.

HARRY F. ROACH, OF ST. LOUIS, MISSOURI.

RAIL-JOINT.

1,078,695.

Specification of Letters Patent.

Patented Nov. 18, 1913.

Application filed April 13, 1912. Serial No. 690,620.

To all whom it may concern:

Be it known that I, HARRY F. ROACH, a citizen of the United States, residing at St. Louis, Missouri, have invented a certain new and useful Improvement in Rail-Joints, of which the following is a full, clear, and exact description, such as will enable others skilled in the art to which it appertains to make and use the same.

10 This invention relates to rail-joints of that type which are so designed that the rails can deflect downwardly slightly with relation to the joint at the ends of the joint when a load passes over the joint, thereby 15 practically eliminating reverse strains and causing the load to be transmitted through the center of the joint to the ties without making a fulcrum of the ties and without causing an excessive pumping up and down 20 of the ties due to fulcruming.

One object of my present invention is to provide a rail-joint of the type referred to in which the rail-supporting portion of the joint is formed by two coöperating parts or 25 members on the inside and outside members of the joint.

Another object is to provide a rail-joint of the type referred to which is so designed that there is no liability of kinking or bending 30 the rails vertically when the end bolts of the joints are tightened.

Another object is to provide a rail-joint embodying the characteristics or features above-mentioned, and which is so designed 35 that it can be rolled or forged easily. And still another object is to provide a rail-joint of the type referred to which consists of two girders that embrace the rails and lap over the base flanges thereof, and integral 40 means on said girders for preventing the base flanges of the rails from becoming kinked or bent downwardly at points adjacent the ends of the joint when the end bolts are tightened.

45 Other objects and desirable features of my invention will be hereinafter pointed out.

Figure 1 of the drawings is a side elevational view of a rail-joint constructed in 50 accordance with my invention, the inside member of the joint being broken away and one of the rails being removed so as to more clearly illustrate the construction of the inner face of the outside member of the joint; Fig. 2 is a top plan view of the joint partly

in horizontal section; Fig. 3 is an end elevational view of the joint; Fig. 4 is a vertical sectional view taken on approximately the line 4—4 of Fig. 1; Fig. 5 is an end elevational view illustrating a slight modification of my invention; Fig. 6 is a side elevational view similar to Fig. 1 showing another modification; Fig. 7 is a top plan view partly in horizontal section of the rail-joint shown in Fig. 6; Fig. 8 is an end elevational view of said joint; and Fig. 9 is a vertical cross sectional view taken on the line 9—9 of Fig. 6.

Referring to Figs. 1 to 4, inclusive, of the drawings which illustrate one form of my 70 invention, A and B designate the two members of the joint that embrace the rails, the member A being arranged on the outside of the rails and the member B on the inside or gage side of the rails. Both of said members have vertically disposed webs 1 that extend practically parallel to the webs of the rails, and portions 2 which lap over the base flanges of the rails, the members A and B being preferably reinforced and strengthened 75 by means of horizontally disposed ribs or thickened portions 3 which are spaced far enough below the under side of the heads of the rails at the ends of the joint to permit the rails to deflect slightly at the 80 ends of the joint when a load passes over the joint, as clearly described in my prior Patent No. 1,013,613, dated January 2, 1912. In the form of my invention illustrated in Figs. 1 to 4, inclusive, the outside member 85 A of the joint is provided at its upper edge with a wheel-supporting member 4 of similar design to the wheel-supporting member of the joint described in my prior Patent No. 1,013,613, above-referred to.

In the rail-joint herein shown the rail-supporting portion of the joint is formed by two coöperating parts 5 and 5^a on the members A and B, respectively, of the joint, said parts 5 and 5^a consisting of base plates 100 arranged in the same horizontal plane and provided at approximately the center of the joint with flat surfaces 6 of relatively great area on which the end portions of the base flanges of the rails rest, and inclined surfaces 7 that slope downwardly in opposite directions from the flat horizontal rail-bearing surfaces 6 so as to prevent the base flanges of the rails from normally resting 105 on the end portions of the rail-supporting 110

parts of the joint. By forming the joint in this manner, namely, providing flat rail-supporting surfaces of relatively great area at the center of the joint on which only the 5 end portions of the abutting rails rest and having the remaining portions of the rail-supporting parts of the joint normally spaced away slightly from the base flanges of the rails, I practically eliminate reverse 10 strains and distribute the load to the ties on which the joint rests without making a fulcrum of the ties and without causing a pumping up and down of the ties due to fulcrumming.

15 The portions 2 of the members A and B are so designed that they bear upon the top faces of the base flanges of the rails at the center of the joint and thus securely clamp the end portions of the rails in operative 20 position upon the flat rail-bearing surfaces 6 at the center of the joint, as shown in Fig. 4. The members A and B are held in position and in engagement with the rails by means of bolts 8 that pass transversely through the 25 webs of said members and through the webs of the rails, and as the portions 2 of said member are spaced just far enough away from the rail-supporting parts 5 and 5^a at the center of the joint to receive the base 30 flanges of the rails, the rails will be held securely against vertical and lateral movement at the center of the joint. The rails can deflect downwardly slightly with relation to the members A and B at the ends of the 35 joint, as previously stated, and in order to prevent the rails from becoming kinked or bent vertically when the end bolts of the joint are tightened, I have provided the members A and B with spacing ribs or stops 40 9, as shown in Figs. 2, 3 and 4, which are so proportioned and disposed that they limit the inward movement of the members A and B with relation to the rails and thus prevent the portions 2 of said members from exerting 45 sufficient downward pressure on the base flanges of the rails when the end bolts of the joint are tightened to cause the rails to kink or bend vertically at the ends of the joint. In other words, the members A and B are provided on their inner faces with 50 devices which are so designed that they prevent said members from being drawn inwardly at the ends of the joint far enough to cause the portions 2 of said members to bend 55 the base flanges of the rails downwardly and thus kink the rails vertically when the end bolts of the joint are tightened. I have herein shown the stops or ribs 9 as extending the entire length of the members A and B 60 but this is only for convenience in manufacturing the joint when the joint is rolled as it is only essential that the stops 9 be arranged at the ends of the joint. I prefer to design the stops 9 in such a manner that 65 they do not contact with the vertical webs

of the rails at the center of the joint, and also round off the ends of said stops at 9^a, as shown in Fig. 2, so that the ends of said stops will not bite into the webs of the rails or nick the rails. By forming the rail-joint 70 in this manner I obtain an exceptionally strong and serviceable structure as the joint comprises two girders arranged parallel to the rails on opposite sides of the rails, and provided with coöperating rail-supporting 75 portions which are so designed that the rails can deflect downwardly slightly at the ends of the joint when a load passes over the joint, thereby practically eliminating reverse strains and distributing the load to the ties 80 on which the joint rests without causing the ties to pump up and down. The rail-supporting portion of the joint may be formed lighter in view of the fact that it is divided and connected to both members of the joint, 85 thus reducing the weight and cost of manufacturing the joint without impairing its efficiency.

If desired, the wheel-carrying member or tread member 4 on the outside member A of 90 the joint that comes into service after the heads of the rails have worn down can be omitted, and both the inside and outside members of the joint formed in the same manner, as shown in Fig. 5. Instead of providing the members A and B with stops or other devices that bear against the webs of the rails and thus limit the inward movement of said members when the end bolts of the joints are tightened, the two members 100 of the joint that embrace the rails can be so formed that the portions thereof which lap over the base flanges of the rails are spaced slightly away from the base flanges of the rails at the ends of the joint, thus permitting 105 said members to move inwardly when the end bolts of the joint are tightened without causing the portions thereof that lap over the base flanges of the rails to exert downward pressure on the rails at the end of the 110 joint. In Figs. 6 to 9, inclusive, I have illustrated a rail-joint constructed in the manner just described, the two side members A' and B' being provided with portions 115 2^a that bear snugly upon the base flanges of the rails at the center of the joint but are spaced away slightly from the top faces of the base flanges of the rails at the ends of the joint, as shown in Fig. 8. The rail-supporting portions 15 and 15^a of the 120 members A' and B', respectively, are provided with flat rail-bearing surfaces 6^a at the center of the joint, and downwardly inclined rail-bearing surfaces 7^a which are normally spaced away from the rails so as 125 to securely hold the terminals of the rails but still permit the rails to deflect slightly at the ends of the joint when a load passes over the same. When the end bolts of the 130 joint are tightened the members A' and B'

will be drawn inwardly toward the rails, but as said members are so designed that portions of same come into contact with the edges of the base flanges of the rails before the portions 2^a at the ends of the joint come into engagement with, or exert downward pressure on, the base flanges of the rails, there is no liability of bending the rails vertically when the end bolts of the joint are tightened. If desired, the portions of the members A' and B' which contact with the edges of the base flanges of the rails when the end bolts are tightened, can be rounded off at the ends of said members, as indicated by the reference character 9^b in Fig. 7, so as to prevent nicking of the rails.

In addition to the desirable features previously mentioned, a rail-joint of the character above-described is admirably adapted for use with electrically-bonded rails because there is sufficient space between the webs of the rails and the two side members of the joint to receive heavy cables 16 that form a bond between the rails, said cables being shown in broken lines in Figs. 3, 4, 5, 8 and 9.

Having thus described my invention, what I claim as new and desire to secure by Letters Patent is:

1. A rail-joint comprising members that are arranged on opposite sides of the rails, and coöperating rail-supporting portions on said members which are so designed that the rails can deflect downwardly slightly at the ends of the joint when a load passes over the joint.

2. A rail-joint comprising members that are arranged on opposite sides of the rails, and coöperating rail-supporting portions on said members having approximately flat surfaces at the center of the joint on which the terminals of the rails bear.

3. A rail-joint comprising members arranged on opposite sides of the rails and provided with coöperating rail-supporting portions that have flat rail-bearing surfaces at approximately the center of the joint, and independent rail-bearing surfaces which incline downwardly in opposite directions from said central rail-bearing surfaces.

4. A rail-joint comprising members that are arranged on opposite sides of the rails, coöperating rail-supporting portions on said members arranged in the same horizontal plane and each being provided with a rail-bearing surface at approximately the center of the joint on which the terminals of the rails rest, and independent downwardly inclined rail-bearing surfaces which are normally spaced away from the rails.

5. A rail-joint comprising members arranged on opposite sides of the rails and provided with coöperating rail-supporting portions which have rail-bearing surfaces on which the terminals of the rails rest, and

independent rail-bearing surfaces that are normally spaced away from the rails but which are engaged by the rails when a load passes over the joint, and means on said members which bears upon the base flanges of the rails and holds them down upon the rail-bearing surfaces at the center of the joint. 70

6. A rail-joint comprising members arranged on opposite sides of the rails and provided with coöperating rail-supporting portions that have approximately flat rail-bearing surfaces at the center of the joint on which the terminals of the rails rest, the remainder of said rail-supporting portions being normally spaced away from the under sides of the base flanges of the rails, and portions on said members that lap over the base flanges of the rails and hold them down securely on the rail-bearing surfaces at the center of the joint. 80

7. A rail-joint comprising members arranged on opposite sides of the rails and provided with coöperating rail-supporting portions which have rail-bearing surfaces at approximately the center of the joint on which the terminals of the rails normally rest and independent rail-bearing surfaces adjacent the ends of the joint which are normally spaced away from the under side of the base flanges of the rails, portions on said members that lap over the base flanges of the rails, and bolts that pass transversely through the rails and through said members, said members being so designed that the portions of the same which lap over the base flanges of the rails will not cause the rails to kink or bend vertically when the end bolts of the joint are tightened. 90

8. A rail-joint comprising members arranged on opposite sides of the rails and provided with coöperating rail-supporting portions, means for supporting and clamping the end portions of the rails, and means for permitting the rails to deflect slightly at the ends of the joint when a load passes over the joint. 100

9. A rail-joint comprising members arranged on opposite sides of the rails and provided with coöperating rail-supporting portions, means for supporting and clamping the end portions of the rails, means for permitting the rails to deflect slightly at the ends of the joint when a load passes over the joint, and a wheel-tread portion on one of said members that extends across the joint or open space between the heads of the abutting rails. 110

10. A rail-joint comprising members arranged on opposite sides of the rails and provided with coöperating rail-supporting portions, means for supporting and clamping the end portions of the rails, means for permitting the rails to deflect slightly at the ends of the joint when a load passes over the joint, and a wheel-tread portion on one of said members that extends across the joint or open space between the heads of the abutting rails. 120

11. A rail-joint comprising members arranged on opposite sides of the rails and

the ends of the joint when a load passes over the joint, and a wheel-carrying portion on one of said members that extends across the open space or joint between the heads of the abutting rails, said wheel-carrying portion having a twisted wheel-tread surface.

11. A rail-joint comprising members arranged on opposite sides of the rails and provided with coöperating rail-supporting portions which are so designed that the rails are firmly supported at the center of the joint but can deflect downwardly slightly adjacent the ends of the joint when a load passes over the joint, portions on said members which lap over the base flanges of the rails, and means for preventing said members from being drawn inwardly far enough when the end bolts of the joint are tightened to cause the rails to be bent or kinked vertically adjacent the ends of the joint.

12. A rail-joint comprising members arranged on opposite sides of the rails and provided with coöperating rail-supporting portions which are so designed that the rails are firmly supported at the center of the joint but can deflect downwardly slightly adjacent the ends of the joint when a load passes over the joint, portions on said members which lap over the base flanges of the rails, and devices on said members that cooperate with the webs of the rails to limit the inward movement of said members relatively to the rails.

13. A rail-joint comprising members arranged on opposite sides of the rails and provided with coöperating rail-supporting portions which are so designed that the rails are firmly supported at the center of the joint but can deflect downwardly slightly adjacent the ends of the joint when a load passes over the joint, portions on said members which lap over the base flanges of the rails, and integral stops on the inner sides of said members which are adapted to engage the webs of the rails at the ends of the joint when the end bolts are tightened and thus limit the inward movement of said members toward the rails.

14. A rail-joint comprising rolled members arranged on opposite sides of the rails and provided with coöperating rail-supporting portions which are so designed that the rails are supported firmly at the center of the joint but can deflect downwardly slightly adjacent the ends of the joint when a load passes over the joint, portions on said members that lap over the base flanges of the rails, and integral horizontally disposed ribs on the inside of said members which are so proportioned that they bear against the webs of the rails at the ends of the joint when the end bolts of the joint are tightened.

15. A rail-joint comprising rolled members arranged on opposite sides of the rails

and provided with coöperating rail-supporting portions which are so designed that the rails are supported firmly at the center of the joint but can deflect downwardly slightly adjacent the ends of the joint when a load passes over the joint, portions on said members that lap over the base flanges of the rails, inwardly projecting stops on the inner sides of said members adjacent the ends of the same which coöperate with the webs of the rails to limit the inward movement of said members with relation to the rails, said stops being so designed that they will not cut or nick the rails.

16. A rail-joint comprising two girders arranged on opposite sides of the rails and provided with coöperating rail-supporting portions which support the rails firmly at the center of the joint but permit the rails to deflect downwardly slightly adjacent the ends of the joint when a load passes over the joint, and integral portions on said girders that lap over the base flanges of the rails and hold the terminals of the rails securely in position.

17. A rail-joint comprising two members arranged on opposite sides of the rails and provided with coöperating rail-supporting portions which have rail-bearing surfaces adjacent the center of the joint on which the terminals of the rails rest and independent rail-bearing surfaces which are normally spaced away from the rails so as to permit the rails to deflect slightly adjacent the ends of the joint when a load passes over the joint, and rail flange engaging portions on said members having inclined surfaces which bear upon the top faces of the flanges of the rails at the center of the joint but are spaced slightly away from the flanges of the rails at the ends of the joint so that they will not exert downward pressure on the rails at the ends of the joint when the end bolts of the joint are tightened.

18. A rail-joint comprising members arranged on opposite sides of the rails and provided with coöperating rail-supporting portions that have rail-bearing surfaces at approximately the center of the joint on which the terminals of the rails normally rest, portions on said members that lap over the base flanges of the rails, and bolts that pass transversely through said members and rails, said members being so designed that the portions of the same which lap over the base flanges of the rails will not cause the rails to bend or kink vertically when the end bolts of the joint are tightened.

19. A rail-joint comprising members that are arranged on opposite sides of the rails, coöperating rail-supporting portions on said members which are so designed that the rails can deflect downwardly slightly at the ends of the joint when a load passes over the joint, and portions on said members which

- lap over the base flanges of the rails and hold them down upon said rail-supporting portions at the center of the joint.
20. A rail-joint comprising members that are arranged on opposite sides of the rails, coöperating rail-supporting portions on said members having approximately flat surfaces at the center of the joint on which the terminals of the rails bear, and portions on said members which lap over the base flanges of the rails and hold them down on said approximately flat rail-bearing surfaces. 70
21. A rail-joint comprising members arranged on opposite sides of the rails and provided with coöperating rail-supporting portions that have flat rail-bearing surfaces at approximately the center of the joint, independent rail-bearing surfaces which incline downwardly in opposite directions from said central rail-bearing surfaces, portions on said members which lap over the base flanges of the rails and hold them down on the rail-bearing surfaces at the center of the joint, and bolts that pass transversely through the rails and through said members, said members being so designed that the portions of the same which lap over the base flanges of the rails will not cause the rails to kink or bend vertically when the end bolts of the joint are tightened. 75
22. A rail-joint comprising members that are arranged on opposite sides of the rails, coöperating rail-supporting portions on said members arranged in the same horizontal plane and each provided with a rail-bearing surface at approximately the center of the joint on which the terminals of the rails rest, independent downwardly inclined rail-bearing surfaces which are normally spaced away from the rails, and portions on said members which lap over the base flanges of the rails and hold them down upon the rail-bearing surfaces at the center of the joint. 80
23. A rail-joint comprising members that are arranged on opposite sides of the rails, coöperating rail-supporting portions on said members which are so designed that the rails can deflect downwardly slightly at the ends of the joint when a load passes over the joint, portions on said members which lap over the base flanges of the rails and hold them down upon said rail-supporting portions at the center of the joint, and bolts that pass transversely through the rails and through said members, said members being so designed that the portions of the same which lap over the base flanges of the rails will not cause the rails to kink or bend vertically when the end bolts of the joint are tightened. 85
24. A rail-joint comprising members that are arranged on opposite sides of the rails, coöperating rail-supporting portions on said members having approximately flat surfaces at the center of the joint on which the terminals of the rails bear, portions on said members which lap over the base flanges of the rails and hold them down on said approximately flat rail-bearing surfaces, and bolts that pass transversely through the rails and through said members, said members being so designed that the portions of the same which lap over the base flanges of the rails will not cause the rails to kink or bend vertically when the end bolts of the joint are tightened. 90
25. A rail-joint comprising members that are arranged on opposite sides of the rails, coöperating rail-supporting portions on said members arranged in the same horizontal plane and each provided with a rail-bearing surface at approximately the center of the joint on which the terminals of the rails rest, independent downwardly inclined rail-bearing surfaces which are normally spaced away from the rails, portions on said members which lap over the base flanges of the rails and hold them down upon the rail-bearing surfaces at the center of the joint, and bolts that pass transversely through the rails and through said members, said members being so designed that the portions of the same which lap over the base flanges of the rails will not cause the rails to kink or bend vertically when the end bolts of the joint are tightened. 95
26. A rail-joint comprising members that are arranged on opposite sides of the rails, coöperating rail-supporting portions on said members arranged in the same horizontal plane and each provided with a rail-bearing surface at approximately the center of the joint on which the terminals of the rails rest, independent downwardly inclined rail-bearing surfaces which are normally spaced away from the rails, portions on said members which lap over the base flanges of the rails and hold them down upon the rail-bearing surfaces at the center of the joint, and bolts that pass transversely through the rails and through said members, said members being so designed that the portions of the same which lap over the base flanges of the rails will not cause the rails to kink or bend vertically when the end bolts of the joint are tightened. 100
27. A rail-joint comprising members that are arranged on opposite sides of the rails, coöperating rail-supporting portions on said members having approximately flat surfaces at the center of the joint on which the terminals of the rails bear, means for clamping the end portions of the rails, and means for permitting the rails to deflect slightly at the ends of the joint when a load passes over the joint. 105
28. A rail-joint comprising members arranged on opposite sides of the rails and provided with coöperating rail-supporting portions that have rail bearing surfaces at approximately the center of the joint on which the terminals of the rails normally rest, portions on said members that lap over the base flanges of the rails and bear on the top faces of said flanges at approximately the center of the joint, and bolts that pass transversely through said members and rails, said members being so designed that the 110
29. A rail-joint comprising members arranged on opposite sides of the rails and provided with coöperating rail-supporting portions that have rail bearing surfaces at approximately the center of the joint on which the terminals of the rails normally rest, portions on said members that lap over the base flanges of the rails and bear on the top faces of said flanges at approximately the center of the joint, and bolts that pass transversely through said members and rails, said members being so designed that the 115
30. A rail-joint comprising members arranged on opposite sides of the rails and provided with coöperating rail-supporting portions that have rail bearing surfaces at approximately the center of the joint on which the terminals of the rails normally rest, portions on said members that lap over the base flanges of the rails and bear on the top faces of said flanges at approximately the center of the joint, and bolts that pass transversely through said members and rails, said members being so designed that the 120
31. A rail-joint comprising members arranged on opposite sides of the rails and provided with coöperating rail-supporting portions that have rail bearing surfaces at approximately the center of the joint on which the terminals of the rails normally rest, portions on said members that lap over the base flanges of the rails and bear on the top faces of said flanges at approximately the center of the joint, and bolts that pass transversely through said members and rails, said members being so designed that the 125
32. A rail-joint comprising members arranged on opposite sides of the rails and provided with coöperating rail-supporting portions that have rail bearing surfaces at approximately the center of the joint on which the terminals of the rails normally rest, portions on said members that lap over the base flanges of the rails and bear on the top faces of said flanges at approximately the center of the joint, and bolts that pass transversely through said members and rails, said members being so designed that the 130

portions of the same which lap over the base flanges of the rails will not cause the rails to bend or kink vertically when the end-bolts of the joint are tightened.

5 29. A rail-joint comprising a pair of members that are arranged on opposite sides of the rails, said members having coöperating portions on which the base flanges of the rails normally bear only at approximately the center of the joint, portions that lap over the base flanges of the rails and bear upon the top faces of said flanges only at approximately the center of the joint, and vertically disposed portions that extend 10 along the webs of the rails, and fastening devices that pass transversely through said vertically disposed portions and through the webs of the rails.

30. A rail-joint comprising a pair of members of girder construction that are arranged 20 on opposite sides of the rails, said members

having coöperating portions on which the base flanges of the rails normally bear only at approximately the center of the joint, portions that lap over the base flanges of 25 the rails and bear upon the top faces of said base flanges at approximately the center of the joint, and vertically disposed portions that extend along the webs of the rails but which do not bear against the underside of 30 the heads of the rails at the ends of the joint, and fastening devices that pass transversely through said vertically disposed portions and through the webs of the rails.

In testimony whereof I hereunto affix my 35 signature in the presence of two witnesses, this ninth day of April 1912.

HARRY F. ROACH.
